DESIGN FOR A COMBINED BRACKET AND MEMORANDUM PAD

John C. Meeks, Woodland, Calif.

Application February 29, 1944, Serial No. 112,747

Term of patent 7 years

(Cl. D74—1)

To all whom it may concern:

Be it known that I, John C. Meeks, a citizen of the United States and a resident of the city of Woodland, county of Yolo, State of California, have invented a new, original, and ornamental Design for a Combined Bracket and Memorandum Pad, of which the following is a specification, reference being had to the accompanying drawing, forming a part thereof.

I claim:

The ornamental design for a combined bracket and memorandum pad, as shown.

JOHN C. MEEKS.
